UNITED STATES PATENT OFFICE.

GERRITT SMITH, OF ASTORIA, NEW YORK.

TELEGRAPHIC RECEIVING-INSTRUMENT.

SPECIFICATION forming part of Letters Patent No. 254,061, dated February 21, 1882.

Application filed December 29, 1881. (No model.)

To all whom it may concern:

Be it known that I, GERRITT SMITH, a citizen of the United States, residing at Astoria, in the county of Queens and State of New York, have invented certain new and useful Improvements in Telegraphic Receiving-Instruments, of which the following is a specification.

The general object of my invention is to attain a greater degree of rapidity and certainty 10 of action in telegraphic receiving-instruments than has been possible with the apparatus hitherto employed for that purpose, and to provide an instrument which is especially adapted for use upon long and imperfectly-insulated 15 telegraph-lines or in cases where unusual rapidity of signaling is required; and these ends I attain by actuating the moving portion of the receiving-instrument—that is to say, the armature and its attached lever, which produces 20 audible sounds, carries a recording stylus or pen, or serves to open and close an independent electric circuit when utilized as a relay or repeater—through the instrumentality of a constant mechanical power controlled by electro-magnetism, instead of actuating the armature and its lever, as heretofore, solely by the direct 25 attractive force of an electro-magnet.

In the accompanying drawings, Figure 1 is a plan view of an apparatus embodying my invention, part of which is broken away to exhibit the internal construction; and Fig. 2 is a transverse vertical section taken in the plane of the dotted line 2 in Fig. 1.

In the drawings, A represents a suitable base 35 upon which the various parts of the apparatus are mounted.

B is a helix or coil of thin insulated wire, which is wound upon an upright hollow spool or bobbin, b, the lower flange, b', of which is 40 preferably formed of hard rubber or other insulating material.

C is a cylinder of magnetic metal, preferably of soft iron, fitting closely within the central opening of the hollow bobbin b, but capable of 45 rotating freely upon its axis. The cylinder C forms the core of the helix B. It preferably has a flange, c, formed upon its upper end.

From the lower end of the cylinder C projects a spindle, c', upon which is fixed a small 50 pulley, D, beneath the base A. A belt or band, d, passes around the small pulley D, and also

around a large pulley, E, which is also mounted in the same plane underneath the base A, as shown in dotted lines in Fig. 1.

A crank, F, is affixed to that portion of the 55 shaft e of the pulley E which projects above the base, by means of which crank it may be turned by the hand by the receiving-operator in the direction indicated by the arrow. When the crank F is thus turned the soft-iron cylinder C, which forms the core of the hollow helix B, is caused to rotate rapidly in the direction indicated by the arrows in Fig. 1.

The upper surface of the cylinder C is polished, and is moreover carefully turned and 65 fitted, so as to revolve as accurately as possible in a horizontal plane.

H is an armature, preferably formed of a thin flat disk of soft iron, a portion of the periphery of which rests upon the upper surface of the 70 cylinder C near the edge of the flange, as shown in Figs. 1 and 2. The disk or armature H is capable of moving freely in a horizontal plane upon its vertical pivot or axis h; but the extent of this horizontal motion is limited by a rigid 75 arm or lever, I, which is fixed to the armature and moves with it, and which plays between fixed stops J and K. These stops may with advantage be rendered adjustable by means of a set-screw or other well-known or equivalent 80 device, as shown in Fig. 1. The stop J is mounted upon a standard, L, attached to the base A, while the stop K is mounted upon a block, l, secured to but insulated from the standard L.

The retractor M consists of a spiral spring attached to the armature H at a point in its periphery diametrically opposite to the point of attachment of the arm I. The retractor may be adjusted by means of the milled head N and 90 spindle n, or other equivalent device, so as to exert a constant force of any required amount upon the armature I.

The helix B terminates in the projecting wires w w, which are electrically connected to 95 the binding-screws W' W², and serve to form a connection with the main line.

When the apparatus is to be used as a relay or repeater the armature H is electrically connected by means of the wire x with the binding-post X, and in like manner the standard L is connected by means of the wire y with the 100

binding-post Y, and the bracket *l* may also be connected by the wire *z* with the binding-post Z.

The apparatus thus constructed is placed in the circuit of a telegraph-line, the connections being completed in the ordinary manner by means of a wire, *w'*, connecting the binding-post W' with the earth at the receiving-station, while the line-wire *w* coming from the transmitting-station is attached to the binding-post 5 W'. The key at the transmitting-station may be arranged to open and close the circuit of the main battery T, as shown at Q', or it may be inserted in a well-known manner, as shown at Q², so that when closed it will shunt a constant resistance, R, normally interposed in the line, and thus act simply to alternately increase and decrease the strength of current in the line without interrupting the circuit.

The operation of the apparatus is as follows: 10 When a telegraphic communication is to be received upon the instrument the cylinder C, which forms the core of the coil B, is caused to rotate upon its axis in the direction indicated by the arrows, which may be effected by turning the crank F, as hereinbefore explained. So long as no electric current traverses the coil B the friction between the cylinder C and the armature H, which rests lightly upon it, will be so small that the cylinder will have but a 15 slight tendency to drag the armature along with it, and this tendency will be overcome by the resistance of the spring N, so that the armature will remain in its normal position, (shown in Fig. 1,) the arm I resting in contact with the stop K. When, however, an electric current is transmitted through the line, as by the depression of the key Q', the cylinder C instantly becomes magnetic under the influence of the coil B and attracts the armature H, which rests 20 upon its periphery. The pressure produced by this magnetic attraction increases the friction between the two surfaces to such an extent that the antagonistic force of the retracting-spring M is overcome, and the armature H is 25 caused to turn upon its axis by the force imparted thereto by the friction of the rotating cylinder C. Hence the arm I is brought into contact with the stop J, in which position it remains as long as the electric current continues 30 to traverse the coil B.

When the current is interrupted by the raising of the key Q' the attraction between the cylinder C and the armature H ceases and the recoil of the spring M instantly restores the armature and its attached arm to their normal 35 position.

In case it is desired to operate the apparatus by an alternate increase or decrease in the strength of a constant current—as, for example, by manipulating the key Q²—the tension of the retracting-spring M is so adjusted that the friction due to the magnetism induced by the normal or minimum strength of current is not quite sufficient to overcome its tension; but 40 any increase of friction beyond the normal amount will overcome the spring and instant-

taneously produce a lateral movement of the armature in the manner hereinbefore explained.

The apparatus has been shown in the drawings in a form particularly adapted for use as 70 a relay or repeater, in which case the terminal wires of an independent receiving-instrument, S, and local battery's are connected to the binding-screws X and Y, in which case the independent circuit will be closed in the same manner as by the lever of an ordinary relay whenever the arm I is brought into contact with the stop J.

It is obvious that the ordinary telegraphic signals may be distinguished by the ear upon 80 this instrument in the well-known manner heretofore practiced by expert telegraphists, the requisite sounds being produced by the vibration of the arm I between the fixed stops J and K.

I claim as my invention—

1. The combination, substantially as hereinbefore set forth, of a rotating cylinder of magnetic metal, a magnetizing-coil acting upon said cylinder, an armature maintained in permanent magnetic contact with the moving surface of said cylinder and capable of receiving motion therefrom by friction, a retractor exerting a constant force upon said armature in a direction opposed to that derived from its 95 frictional contact with the moving cylinder, and fixed stops for limiting the movements of the armature in each direction.

2. The combination, substantially as hereinbefore set forth, of a rotating cylinder of magnetic metal, a magnetizing-coil acting upon said cylinder, an armature maintained in permanent magnetic contact with the moving surface of said cylinder and capable of receiving motion therefrom by friction, a retractor exerting a constant force upon said armature in a direction opposed to that derived from the moving cylinder, an electric circuit including 100 said magnetizing-helix, and a key or transmitter in said circuit for alternately increasing 105 and decreasing the strength of the current traversing said circuit.

3. The combination, substantially as hereinbefore set forth, of a rotating cylinder of magnetic metal, a magnetizing-coil acting upon 110 said cylinder, an armature maintained in permanent magnetic contact with the moving surface of said cylinder and capable of receiving motion therefrom by friction, a retractor exerting a constant force upon said armature in 115 a direction opposed to that derived from the moving cylinder, and an independent circuit traversed by an electric current which is controlled by the movements of said armature.

In testimony whereof I have hereinunto subscribed my name this 24th day of December, 125 A. D. 1881.

GERRIT SMITH.
